CONTAINER SHIP FOR HANDLING
PACKAGE FREIGHT

Leathem D. Smith, Sturgeon Bay, Wis.; Alva
Smith administratrix of said Leathem D.
Smith, deceased

Application April 22, 1944, Serial No. 532,240

9 Claims. (Cl. 114—72)

1

The invention relates to a container ship capable of storing package freight containers in one or more holds and has reference in particular to an improved construction of container ship having fixed beams in the holds for supporting the containers with open hatches to facilitate access thereto.

An object of the invention is to provide an improved construction of container ship for accommodating the compact storage of package freight containers within one or more holds of the ship and which improved construction may be embodied in the self-unloader type of ship or in a ship without the self-unloading feature so that full use may be made of their cargo carrying capacity.

For transporting miscellaneous cargo such as boxes, crates and the like, collectively termed "package freight", the invention provides wheelless containers for the same, thereby making it possible to transport such miscellaneous freight from any shipping point to its destination without rehandling, repacking or crating that would otherwise be necessary. The containers are of standard size and a convenient number may therefore be carried on any conventional railroad flat car. This permits the containers to be initially loaded by the manufacturer or shipper, sent over the railroad to the loading terminal for the container ship, and stored in the ship in a manner requiring the minimum of time, effort and space, with the result that intermediate handling of the individual packages is entirely eliminated.

Another object is to provide a container ship having fixed beams in one or more holds and by substantially eliminating the top deck large open hatches are formed so that ready access may be had for placing the package freight containers in position on the beams or for removing the containers therefrom.

A further object of the invention is to provide a container ship having open fixed beams for supporting a plurality of package freight containers within one or more holds of the ship and which beams will be notched for receiving the containers in a manner to securely lock them in place.

A further object is to provide a container ship having one or more holds equipped with container supporting beams of special notched arrangement and forming different levels within the hold with the beams alternately extending longitudinally and transversely as regards the different levels.

With these and various other objects in view,

2

the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a part elevational and part vertical sectional view of a cargo vessel of the self-unloader type illustrating the container supporting beams within the various holds and the gantry crane on the top deck in accordance with the invention;

Figure 2 is a vertical sectional view of the ship shown in Figure 1 illustrating the manner of storing the package freight containers on the supporting beams therefor;

Figure 3 is a vertical transverse sectional view of a ship having a flat tank bottom equipped with the container supporting beams in accordance with the invention;

Figure 4 is a vertical sectional view taken longitudinally through a portion of the ship of Figure 3 and showing the arrangement of the container supporting beams within a hold of the ship;

Figure 5 is a horizontal plan view taken substantially along line 5—5 of Figure 3 illustrating the notched construction of the supporting beams and the arrangement of package freight containers in supported relation on the beams;

Figure 6 is a side elevational view of a package freight container embodying the improved features of the invention;

Figure 7 is an end elevational view of the container shown in Figure 6;

Figure 8 is a fragmentary top plan view of the container;

Figure 9 is a detail view, parts being shown in section, of one end of a spring tension tie rod for the containers;

Figure 10 is an elevational view showing the container in collapsed position;

Figure 11 is a perspective view showing the socket for receiving and releasably locking the headed end of a top pipe batten for the container; and

Figure 12 is a fragmentary sectional view illustrating the manner of removably fastening the end pipe battens to the side walls of the container.

Referring to the drawings, particularly Figures 1 and 2, the numeral 10 indicates the hull of a vessel having several cargo holds 11 extending

for a part of the vessel's length, said holds being formed by the transverse bulkheads 12 and having one or more open hatches 13 providing access to the holds. Conveyor tunnels 14 and 15, Figure 2, extend longitudinally of the ship under the several holds 11 for removing the cargo therefrom in the event one or more of the holds have been employed for transporting bulk cargo in the place of the package freight containers. As best shown in Figure 2 the tunnels 10 are each provided with oppositely inclined roof members 16 and 17. The roof members direct the material to the respective sides of the tunnels from which the inclined bottom members of the vessel direct the material to within the tunnels. As evident from Figure 2, a tunnel is located on each side of the longitudinal center line of the vessel and along this center line the inclined members 18 comprise the bottom members of the hold. On the opposite side of each tunnel the sloping side members 19 form the bottom of the hold. When the doors of each tunnel are open material enters the tunnels and is removed by scrapers in a manner well known and understood in the self-unloader type of boats.

For purposes of the present invention the boat shown in Figure 1 is provided on its top deck with a whirley 20 and with a travelling gantry crane 21. Said crane is adapted to travel longitudinally of the top deck on the rails 22, as shown in Figure 2, and therefore the crane can be used to load and unload any one of the holds 11 with the containers. Said crane essentially consists of end uprights 23 which have rolling contact on the rails 22. The end uprights are joined by the trussed and reinforced horizontal member 24 provided with a suitable guideway adapted to accommodate the wheeled carriage 25, which accordingly has movement from one side of the gantry crane to the other. To facilitate the handling of the containers with respect to the dock or loading terminal for the vessel the gantry crane is provided with an extension 26 having pivotal connection with one side of the adjacent end member 23. When the extension 26 is extended, as shown in Figure 2, a supported guideway over which the carriage 25 is able to travel is provided above the dock, and it is therefore possible to lift the containers directly from the dock and store them in the hold of the vessel or to unload the same directly onto the dock. When not in use the extension 26 is folded back in contact with the horizontal member 21 and in this position the same is out of the way although readily available for use at any time.

For accommodating the compact storage of the package freight containers within one or more holds of the ship the invention contemplates an open beam construction. More particularly, each hold, or as many holds as may be desired, are equipped with notched beams forming different levels within the hold and large open hatches are provided to facilitate access to the beams. In order that package freight containers of standard size may pass through one level and be supported on the notched beams at a different level, the supporting beams alternately extend longitudinally and transversely as regards said levels. The construction is clearly evident from an inspection of Figures 1 and 2, illustrating the self-unloader type of ship and also Figures 3 and 4, which show the conventional type having the flat tank bottom.

As previously explained, the several holds 11 are formed by the transversely extending

partitions or bulkheads 12. The longitudinal beams 29, Figures 1 and 2, therefore extend from bulkhead to bulkhead, whereas the transverse beams 28 and 30 extend from one side wall 31 of the hold 10 to the opposite side wall 32. The side walls 31 and 32 are reinforced and strengthened at intervals by the vertically extending beams 33. The transverse beams 28 and 30 are suitably secured at their respective ends to the vertical beams 33. The longitudinally extending beams 29 are also supported in any suitable manner at their respective ends from the bulkheads and it will be observed from Figure 2 that notched horizontally extending brackets 34 are provided to take the place of the beams adjacent the side walls of the vessel.

In Figures 3 and 4 of the hold of a conventional ship having a flat tank bottom is shown equipped with the open beam construction for storing the containers. The hull of the vessel indicated by numerals 35 has side walls 36 and 37 which are reinforced at intervals on the inside of the boat by the vertical members 38. The transverse supporting beams 40 are secured at their respective ends to these members by the brackets 41. The longitudinal supporting beams 42 extend from bulkhead to bulkhead and brackets 43 or similar means are employed in securing the beams to said bulkheads. If additional support is required the uprights 44 and 45 may be employed intermediate the ends of the beams. The beams are T-shape in cross section and they are large enough to accommodate the uprights. Certain uprights will contact the lower small flange of the beams and as regards the top horizontal flange, the uprights may contact the middle area, leaving the overhanging flanges on each side as supporting portions for the containers. Uprights 45 rest on the flat tank bottom 39 and support the beams 42, whereas, the uprights 44 extend between beams 40 and 42.

Figure 5 illustrates the manner in which the side edges of the beams are notched at regular intervals. The notches 46 and 47 receive the legs of the container and are spaced a distance equal to the over-all width of the container. In other words, the distance between notches 46 and 47 is actually the distance between the legs on the shorter side of the container. The beams are spaced a distance measured from center to center slightly greater than the length between the legs of the container.

In accordance with the invention the containers are rectangular in plan and therefore the distance between notches 46 and 47 is less than the space between the side edge of one beam and the side edge of the next adjacent beam. This manner of spacing the beams renders it possible to lower the containers past certain beams for support on beams forming the lower level. The containers are sufficiently narrow to pass through the space between beams and the beams on the level below are properly arranged for receiving and supporting them, provided the transverse and longitudinal positioning of the beams for the different levels is employed.

The notches 46 and 47 are formed in the horizontal flange of the T-shaped beam. Each notch receives a leg of the container and the portion 48 therefore provides the support for the container. It is not necessary to use ropes, cables or the like for lashing the containers since they are securely locked in place by the notches. For any particular level formed by the beams, such as that formed by the longitudinal beams

42 in Figure 5, auxiliary brackets 50 are provided to supplement the beams. In said figure the brackets extend along and are suitably secured to the side walls 36 and 37. For the transverse beams 40 similar brackets 51 extend along and are secured to the bulkheads.

For maximum utilization of the space within the hold of the ship it is necessary to locate the containers as close to each other as possible. As shown in the drawings very little space is left unoccupied. By providing one or more large hatches over the hold the containers are easily located within or removed from the holds. This speeds up the loading and unloading and reduces the time required for the ship to remain in dock. The container ship and the package freight containers to be presently described in detail also eliminate intermediate handling of the individual packages and further eliminate hand handling of the cargo on the ship.

The collapsible container of the invention is shown in side and end elevational views in Figures 6 and 7. Numeral 55 indicates the floor plate of the container, which is supported in elevated position by four legs, numeral 56 indicating the two legs adjacent the left end of the container, Figure 6, and numeral 57 indicating the two legs adjacent the right end. The legs comprise corner elements of the container and have a right angled shape in cross section. End floor channels 58 are located at each end of the floor plate, being suitably secured thereto and which in turn form securing means for the legs of the container. The sides of the floor plate 55 are provided with base plates 59 and 60 which are of greater height than the end channels 58 and thus extend above the floor. Said base plates likewise have the legs of the container secured thereto, whereby the bottom portion of the container constitutes an integral unit with the floor plate, channels, base plates and legs all being secured to one another. The base plates 59 and 60 are reinforced at intervals by the vertical stiffeners 61 and plate brackets 62 extend from each side plate to the floor plate at the respective ends of the same.

From an inspection of Figures 7 and 10 it will be observed that the base plate 60 extends above the floor plate to a height somewhat in excess of that of base plate 59. This construction is resorted to in order to make possible the collapsing of the container, as best shown in Figure 10. The side uprights 63 and 64 are each fabricated from structural parts, as shown by Figure 6, and each upright is pivotally secured along its bottom edge to one of the base plates comprising an integral part of the container. A full hinge 65 and two half hinges 66 and 67 may be employed. Each upright essentially consists of a top brace channel 68, a bottom brace channel 69, and end channel members 70 and 71. The parts are suitably secured to form a substantially rectangular frame which is reinforced and strengthened by the diagonally extending braced channels 72 and the horizontally extending channels 73. Plate brackets 74 may be located at one or more corners and the channels 72 may be additionally secured to the top and bottom channels by means of plate brackets such as 75. For lifting the containers two or more lift rings 76 are suitably secured in spaced relation to the top brace channel 68.

Since each side upright is pivotally secured along its bottom edge to one of the base plates forming the bottom portion of the container, it

is necessary to provide releasable means for holding the uprights in vertical position. This structure essentially consists of top pipe battens, indicated by numeral 78, Figures 7 and 8. Batten sockets 79 are suitably secured to the inside surface of the top brace channels 68 of each upright and the top pipe battens are provided at their respective ends with a cap portion 80, see Figure 11. The inside wall of each socket is provided with a centrally positioned pin 81 and the face of each cap portion 80 is formed with a recess or opening 82 somewhat elongated in extent and leading from the circumference of the cap portion to slightly beyond its center. It will therefore be understood that when the top pipe battens are inserted in place with the cap portions 80 entering the sockets, the pins 81 will be received by the recesses or openings 82. The top pipe battens will remain in place unless positively lifted from their sockets but it is relatively simple to lock the battens in place merely by turning them 180 degrees, since the pins 81 will then prevent lifting of the battens from their sockets. The locking action, however, is releasable since the battens need only be turned to properly align the recesses or openings 82 whereby they can be lifted.

The spring tension rods 84 extend diagonally at each end of the container. Said rods serve to prevent a racking distortion to the container when the container is lifted. For collapsing purposes and to also facilitate unloading the spring tension rods are removable. Each rod at one end has connection with a pin 85 extending inwardly from the outer wall of the end channel members 70 and 71. At the opposite end of the tension rods a bayonet type of opening 86, Figure 9, is provided in the enlarged head 87. Said head, by means of the opening, is releasably secured to pin 88 extending inwardly from the plate brackets 62. Each rod has limited spring tension by means of the structure shown in Figure 9. The enlarged head 87 is formed on part 89 of the tension rod, which is separable from the main part 84. By means of the coil spring 90 and its associated structure limited separation is possible, with the result that the tension rod can be releasably secured to parts of the container to apply the desired tension to the uprights. The coil spring 90 is confined between the washer 91 suitably welded to part 89 and the cylinder 92 secured to the main portion 84 of the tension rod by means of the threaded engagement which the cylinder has with the boss 93. Said boss is suitably secured to the terminal end of said main portion 84 of the rod and it will therefore be seen that any tension applied to the rod will permit elongation by compression of coil spring 90.

It will be clear from Figure 7 that the diagonal crossing of the tension rods 84 does not close the end of the container to an extent preventing inadvertent removal or loss of the individual packages stored within the container. However, it is desirable, since the containers embody the collapsing feature, to provide closure means which will be relatively simple in nature and easily removed or installed. For this purpose end pipe battens 94 are employed. For receiving said end pipe battens the end channels 70 and 71 are closed by plates 95. As best shown in Figure 12, the plates 95 are provided with a plurality of openings 96 and each end batten is slotted as at 97. The battens are thus located in their proper opening and dropped into place, with the result that they are releasably held in connected

relation with the uprights. Any number of end battens may be employed, the number primarily being determined by the size of the miscellaneous cargo stored in the container.

The containers above described may be stored within a hold of the container ship by means of the slotted beams, it being understood that the beams are so spaced and that the slots are likewise so spaced as to receive the four legs of a container. Positioning containers on the beams is relatively simple and the construction has the desired advantage in that the slotted beams reasonably lock the containers in place, eliminating the need for lashing of the containers.

To facilitate loading, one or both ends of a container may be left open. When fully loaded the end pipe battens are dropped in place and the tension rods are then applied to the ends of the container. The legs support the container a distance above the floor to render possible the use of lift trucks for moving them from place to place at the loading terminal and on the dock.

From the foregoing the various advantages in transporting miscellaneous freight by the container ship of the invention and package freight containers designed particularly for use therewith may be summarized as follows:

1. Reduction of the loss and cost of individual handling of small items of cargo to and from the ship, together with the elimination of damage to the cargo at these points.
2. Elimination of the danger of shifting of the cargo at sea.
3. Saving ship's time in port by having containers already packed ready for loading.
4. Saving in the expense of dock crews working over time since they can load the containers during regular working hours.
5. Reduction to a minimum of the man power required to handle cargo on the ship over similar designs which require a shifting of the cargo in the holds after it has been lowered through the hatch.
6. Permitting the unloading of partial cargos at intermediate ports quickly and efficiently without undue layover and without making previous arrangements at these ports for dock handling facilities.

The invention is not to be limited to or by details of construction of the particular embodiment thereof illustrated in the drawings as various other forms of the device will of course be apparent to those skilled in the art without departing from the spirit of the invention or the scope of the claims.

What is claimed is:

1. In a ship of the character described, in combination, an open cargo hold having a plurality of spaced beams disposed horizontally within the hold, certain of said beams lying in one horizontal plane and other beams lying in a different horizontal plane, means connecting said beams at their respective ends to the ship structure whereby the beams comprise an integral part thereof, said beams presenting a flat supporting surface for substantially their entire length, and said flat supporting surfaces having pairs of notches to receive fixed elements on uniformly sized containers to hold them against lateral movement.
2. A ship of the character described, as defined by claim 1, wherein a relatively large hatch opening is formed on the top deck of the ship in substantial alignment with the hold to facilitate access to the beams.

3. In a ship of the character described, in combination, an open cargo hold having a plurality of spaced beams disposed horizontally within the hold, certain of said beams lying in one horizontal plane and other beams lying in a different horizontal plane, connecting means for the beams joining them at their respective ends to the ship structure, whereby the beams comprise an integral part thereof, and said beams having notches in spaced relation on the respective sides of the beams for holding against lateral movement fixed elements on containers, the spacing of the beams in any horizontal plane being greater than the maximum longitudinal distance between the notches of any beam when measured from center to center.

4. In a ship of the character described, in combination, an open cargo hold having a plurality of beams horizontally disposed and spaced vertically so as to form different levels within the hold, said beams being substantially fixedly secured at their ends to the ship structure, said beams in cross-section forming a T and presenting a flat supporting surface, and said flat supporting surface having notches formed therein spaced longitudinally of the beams on the respective sides thereof for holding against lateral movement complementary members fixed to containers.

5. A ship of the character described, as defined by claim 4, wherein access to the beams is facilitated by a relatively large hatch opening in the deck substantially the size of the hold in plan and which is directly over the hold.

6. In a ship of the character described, in combination, an open cargo hold, including the space from side wall to side wall of the ship and from one bulk-head to an adjacent bulk-head, a plurality of beams within the hold disposed horizontally and spaced vertically to form different levels within the hold, the horizontally disposed beams of one level extending transversely of the ship from side wall to side wall and the horizontally disposed beams forming another level extending longitudinally of the ship from bulk-head to bulk-head, said beams being substantially fixedly secured at their ends to the ship structure whereby the beams comprise an integral part thereof and each beam presenting a flat supporting surface having notches spaced longitudinally on the respective sides of the same for holding against lateral movement complementary members fixed to containers.

7. In a ship of the character described, in combination, an open cargo hold including the space from side wall to side wall of the ship and from one bulk-head to an adjacent bulk-head, a plurality of beams within the hold disposed horizontally and spaced vertically to form different levels within the hold, the horizontally disposed beams of one level extending transversely of the ship from side wall to side wall and the horizontally disposed beams forming another level extending longitudinally of the ship from bulk-head to bulk-head, each beam presenting a flat supporting surface having notches spaced longitudinally on the respective sides of the same, said beams being substantially fixedly secured at their ends to the ship structure whereby the beams comprise an integral part thereof and the beams of each level being spaced from each other a distance greater than the maximum longitudinal distance between the notches of any beam measured from center to center.

8. In a ship of the character described as de-

fined by claim 7, wherein the horizontally disposed beams alternately extend transversely and longitudinally for the different levels.

9. In a ship of the character described as defined by claim 7, wherein the horizontally disposed beams alternately extend transversely and longitudinally for the different levels, and wherein one or more relatively large hatch openings are formed in the top deck in substantial alignment with the hold to facilitate access to the 10 beams.
